UNITED STATES PATENT OFFICE.

LUCY A. CLOON, OF GOODELL, IOWA.

DESIGN FOR A CLOCK-CASE.

SPECIFICATION forming part of Design No. 34,605, dated June 4, 1901.

Application filed May 7, 1901. Serial No. 59,188. Term of patent 3½ years.

To all whom it may concern:

Be it known that I, LUCY A. CLOON, a citizen of the United States, residing at Goodell, in the county of Hancock and State of Iowa, have invented and produced a new and original Design for a Clock-Case; of which the following is a specification.

This invention relates to a new and original design for a clock-case, and the essential features reside in a base having a cross rising from one extremity thereof, an upright at the opposite extremity, with a crown on the apex thereof, and a figure standing near the cross and pointing upwardly to the crown.

The accompanying drawing represents an elevation of a clock-case embodying the features of the design.

The design is characterized by a base 1 with feet 2, an upright 3 at one extremity of the base, having a curved margin, and a cross 4 at the opposite extremity entwined with sprays of flowers, as at 5. In the upright 3

the clock proper is adapted to be held, as at 6, and surrounding the same is a circular band 7, and on the apex of the upright a crown 8 ²⁵ is represented. Standing close to the cross 4 is a human figure 9 with one hand resting on the top of said cross and the other hand uplifted and pointing to the crown 8. The base 1, cross 4, and band 7 will be distinguished from the remaining features by making them black, and the upright and feet will be gilt. ³⁰

Having thus described the invention, what is claimed as new is—

The design for a clock-case, as herein shown and described.

In testimony that I claim the foregoing as my own I have hereto affixed my signature in the presence of two witnesses.

LUCY A. CLOON.
